APPARATUS FOR TEACHING TELEGRAPHY

Alfred Edward Thompson and Reginald Dennis Salmon, Croydon, England, assignors to Creed and Company Limited, Croydon, England

Application June 13, 1941, Serial No. 397,931
In Great Britain November 22, 1940

2 Claims. (Cl. 178—115)

This invention relates to apparatus for teaching telegraphy. The object of the invention is to provide a simple and cheap form of apparatus for generating telegraph signals for the purpose of training students to interpret such signals.

Such apparatus is more particularly useful for transmitting a standard series of exercises in the Morse code of gradually increasing difficulty.

The nature of the invention will be better understood from the following description of one embodiment thereof taken in conjunction with the accompanying drawings in which:

Figs. 1 and 2 are perspective views of the exercise transmitter, and Fig. 3 shows a detail.

The embodiment of the invention described hereinafter comprises a transmitter for signals in the Morse code, which is intended for transmission of a standard series of exercises.

The dots and dashes of each exercise are recorded as black and white marks on the circumference of a number of cylinders, the marks being arranged in the form of a screw thread or as a continuous circumferential line according to the length of the exercise. Each cylinder is placed as required between rotating centres in the machine and scanned by a beam of light which controls, by means of a photo electric cell, a valve amplifier. The amplifier is provided with two outputs, one output being a tone suitable for use in the headphones and the other output being rectified signals suitable for operating relays that control Morse keys.

All the exercises required for the first twelve lessons of a course of standard exercises are contained on a single cylinder, each exercise being brought into the controlling position by the movement of one lever. The thirteenth lesson of the course in transmission requires two cylinders each carrying two exercises of approximately 6 minutes duration. The course in reception comprises six lessons each requiring one cylinder carrying three exercises of approximately 2½ minutes duration, each exercise being used twice to give the required exercise period of 5 minutes. The cylinders may easily be removed and replaced by withdrawing a spring loaded plunger. When inserting a cylinder into the machine it is only necessary to lay it in a cradle and to release the plunger. The cylinders are made of moulded synthetic resin and the dots and dashes are formed as white marks cut in the surface of the resin and filled in so that the outer surface of the cylinder is quite smooth.

Referring now to the drawings, each cylinder, as it is required, is placed in the machine between

centres 1 and 2. Centre 1 is spring loaded and withdrawable by means of a handle 3. Centre 2 carries a driving dog 4 that is adapted to engage with a pin driven into the end of the drum 5. This centre is driven by means of a gear wheel 6 that meshes with a gear wheel 7 mounted in a slidable manner on the shaft 8 and driven therefrom by means of a spline 9.

The centres 1 and 2 are carried in a frame 10 also adapted to slide endways upon the shaft 8. The shaft 8 is provided with a screwed portion 11 of square form. The frame 10, however, is formed with a plain hole so that it can freely slide over the top of the thread portion of the shaft 8.

A lever 12 mounted upon the frame 10 is provided with a portion in the form of a half-nut as shown more clearly in Fig. 3 so that when the lever 12 is in the position shown in Fig. 1 the half-nut will engage with the thread and thereby cause frame 10 to move endways when the shaft 8 is rotated. The rotation of the shaft 8 will also cause the gear 7 to rotate due to the action of the spline 9 thereby rotating the gear 6 and cylinder 5. Hence the cylinder 5 is caused to move endways whilst it rotates.

The lever 12 may however be turned through 90° as shown in Fig. 3 whereby it is disengaged from the thread 11 and engaged with a stationary rack 13. When the lever 12 is disengaged from the thread 11 the frame 10 may be moved endways manually to engage the lever 12 with any slot of the rack 13.

An optical condenser 14 is arranged to focus light from a lamp 15 upon a small portion of the cylinder 5. An image of the brightly illuminated portion of the cylinder 5 is focussed by means of a lens system 16 upon a diaphragm 17 having therein a small rectangular hole. The beam of light, after passing through the hole in diaphragm 17 is arranged to be interrupted by teeth carried on the periphery of a rotating disc 19 mounted upon the shaft of a driving motor 20, Fig. 2 after which it passes into a photo electric cell 18 which is associated with a vacuum tube amplifier having an output suitable for operating relays. Alternatively, the amplifier is adapted to give a tone output suitable for use in headphones. The shaft 8 is driven from motor 20 through gearing 21 and pulley wheels 22 and 23 the diameters of which are arranged so that the spindle 8 may be driven at one or other of two speeds corresponding to 10 or 16 words per minute, the speed of 10 words per minute being used for lessons in transmission and the speed of 16 words per minute being used for lessons in reception.

The arrangement is such that when the lever 12 is in the position shown in Fig. 1, the cylinder 5 rotates and moves endways. The beam of light from lamp 15 illuminates successively a spiral path upon which the dots and dashes of the exercise are marked so that light reflected therefrom and focussed upon diaphragm 17 is caused to operate the photo electric cell to produce impulses of current therein corresponding to the dots and dashes marked upon the cylinder.

The dots and dashes are recorded as white marks on a black background, the light reflected from these is chopped up by the teeth on the rotating disc 19 so that each dot and dash becomes a group of short impulses, the frequency of which is arranged to produce a tone in the valve amplifier of approximately 1,000 per second. This tone after amplification may be used for operating the headphones, or is rectified and operates a power valve for controlling relays operating a solenoid arranged under a Morse key.

Each dot on the cylinder is approximately $\frac{1}{16}$ " in length and each dash approximately $\frac{3}{16}$ " in length. The spiral traced on the circumference of the cylinder is $\frac{1}{16}$ " pitch and 5" in length. The record provides for continuous transmission of approximately 60 words. Each cylinder may, however, contain more than one exercise and the transmission may be stopped at any moment.

For those exercises which comprise the transmission of a continuous series of the same letter or letters, the cylinder does not move endways whilst it rotates. Each letter or group of letters is formed as a continuous ring on the surface of the cylinder and the cylinder is moved endways to engage lever 12 with a tooth of the rack 13 to bring the desired letter or group into the scanning path.

The cylinder may be quickly removed from the machine and replaced by pulling back centre 1 by means of the handle 3. A cradle underneath the cylinder locates it when it is first placed in

the machine. When the handle 3 is released to re-engage the center 1 with the cylinder, the cylinder is lifted slightly so as to be held clear of the cradle.

It is to be understood that the apparatus could be used to reproduce an exercise consisting of telegraph signals from a record made by a Morse inker on a sheet of paper wrapped around one of the cylinders.

In this case it will, however, be necessary to invert the signals by inserting between the photo-electric cell and the amplifier any well known form of inverting device so that the signals which are as black marks on the cylinder will be reproduced as tones or as operations of the telegraph key.

What is claimed is:

1. A telegraph signal transmitter for teaching telegraphy comprising a cylinder having representations of telegraph signals spirally arranged on its circumference, a carriage for supporting said cylinder in operative position, means for rotating said cylinder, scanning means for scanning said representations to produce signal indications, a threaded spindle mounted for rotation with said cylinder, manually operable means mounted on said carriage for engaging said threaded spindle to advance said carriage upon engagement, and stop means for cooperating with said manually operable means in disengaged position to prevent endwise movement of said carriage.

2. A telegraph signal transmitter according to claim 1, wherein said manually operable means comprises a lever pivotally mounted on said carriage and having a screw thread capable of engaging with the thread on said shaft, and spring means for maintaining said engagement and said stop means comprises a plate having a series of notches for receiving said lever when in disengaged position.

ALFRED EDWARD THOMPSON.
